UNITED STATES PATENT OFFICE.

MATTIA MARANGONI, OF NEW YORK, N. Y.

BOAT-PROPELLING MEANS.

Application filed April 6, 1928. Serial No. 267,933.

This invention relates to a boat propelling means, and comprehends a manually operable propelling means for water craft.

One of the principal objects of the present invention is to provide a manually operable means for driving the propeller shaft of a screw propeller to rotate the same at a materially greater rate of speed than the speed at which the manipulating element is turned.

10 The invention further comprehends in a boat propelling apparatus an upstanding supporting frame secured at its lower end within the hull and which frame includes a stationary base section and a movable upper section 15 normally projecting above the gunwales or confines of the boat and movable to a position within the confines thereof so as not to interfere with the stretching of a covering over the boat when the same is not in use.

20 Other objects of the invention reside in the simplicity of construction of the apparatus, the economy with which it may be produced and installed and the general efficiency derived therefrom.

25 With the above recited and other objects in view, reference is had to the following description and accompanying drawings, in which there is exhibited one example or embodiment of the invention, while the claims 30 define the actual scope of the same.

In the drawings:

Figure 1 is a fragmentary side view of the boat, parts being broken away to illustrate the propelling apparatus installed therein.

35 Figure 2 is an enlarged side view of the propelling apparatus illustrating in full and broken lines the active and inactive positions of the movable frame section.

40 Figure 3 is a sectional plan view taken approximately on the line 3—3 of Figure 2.

Figure 4 is a front face view of the apparatus.

Figure 5 is a fragmentary plan view of a modified form of the invention.

45 Figure 6 is a side view thereof.

Referring to the drawings by characters of reference, 10 designates a screw propeller, 11 a propeller shaft which extends through the hull of a boat and which is provided at its 50 forward end with a beveled pinion 12. A transverse driven counter shaft 13 is suitably supported in bearings 14 and has secured thereto a beveled gear 15 which meshes with the pinion 12. Preferably, the ratio between the gear and pinion is such that the propeller shaft 11 is driven at a higher rate of speed

than the counter shaft 13. The driven counter shaft 13 has also secured thereto a sprocket 16 and a flywheel 17. Spaced from the counter shaft is a supporting frame including a stationary base section 18 and an upper movable section 19 which is preferably connected to the base section by hinges 20. The base section 18 has mounted therein in suitable bearings 21 a drive counter shaft 22 which has secured thereto a drive sprocket 23 around which and the sprocket 16 a sprocket chain 24 is trained for transmitting motion from the drive shaft 22 to the driven shaft 13. Preferably, the gear ratio between the sprockets 16 and 23 is such that the shaft 13 is driven at a higher rate of speed than the shaft 22. The drive shaft 22 has also secured thereto a driven sprocket 25 which is connected by a sprocket chain 26 to a driving sprocket 27 secured to a crank shaft 28 journaled in bearings 29 in the upper movable frame section 19. A crank shaft 28 is provided with an operating crank handle 30 adapted to be manually turned. Preferably, the gear ratio between the sprockets 27 and 25 is such that the latter is driven at a greater rate of speed than the former. The frame section 19 is held in a vertical active position by means of bolts 31 which pass respectively through the overlapped portions 32 and 33 of the upper and base sections and which engage in notches 34 and 35 of said overlapped portions. The frame is of such a length that it projects when in its active position above the confines of the hull but is adapted to be swung to an inactive position within the confines as illustrated in the broken lines in Figures 1 and 2. When swung to the inactive position it is rested on a supporting element 36 which is attached to the hull and projects upwardly therefrom. This permits of the disposition of the frame section 19 below the gunwales so that a tarpaulin or other covering may stretch over the boat.

100 In the modified adaptation of the invention illustrated in Figures 5 and 6, the means for transmitting driving power from the driven counter shaft 13 to the propeller shaft 11 has been varied by the elimination of the beveled gear and pinion 15 and 12. In lieu thereof, the counter shaft 13 has secured thereto a pulley sheave 37 while a stub shaft 38 is provided with a pulley sheave 39. A driving belt or cable 40 is trained around the pulley sheaves 37 and 39 and is also trained around guide sheaves 41. The stub shaft has secured there-

to a sprocket 42 while the propeller shaft 11 has secured thereto a sprocket 43 around which are trained a sprocket chain 44. In other respects, the propelling apparatus is 5 identical with the preferred form of the invention.

In use and operation, the operator turns the crank handle 30 which rotates the crank shaft 28 and through the sprocket and chain 10 connection 25, 26 and 27 the drive counter shaft 22 is rotated at an increased rate of speed. The driven counter shaft 13 through the sprocket and chain connection 16, 23 and 24 is driven from the drive counter shaft 22 15 also at an increased rate of speed while the propeller shaft and its screw propeller 12 are rotated at a further increased rate of speed due to the beveled pinion and gear connection 12 and 15. It is also obvious that by 20 turning the crank handle in opposite directions the propeller may be driven in reversed directions. In order to prevent the sprocket chain 26 from becoming disengaged from the sprockets 25 and 27 when the upper frame 25 section is moved to its inactive position, retaining elements 25^a and 27^a are carried by the frame sections 18 and 19. The elements 25^a and 27^a are provided with notched portions 25^b and 27^b, which portions partially 30 embrace the sprockets where the chains are trained therearound.

What is claimed is:

1. A boat propelling apparatus comprising a propeller shaft, a driven counter shaft operatively connected therewith, a sprocket on the counter shaft, a drive counter shaft spaced therefrom and parallel thereto, a sprocket on said drive counter shaft, a sprocket chain trained around said sprockets and manually operable means connected with the drive shaft comprising an upstanding supporting frame secured at its lower end to the hull of the boat, said frame including a stationary base section and a movable upper section normally projecting above the confines of the boat when the device is in active use and movable to a position within the confines thereof when the boat is in inactive use. 40

2. A boat propelling apparatus comprising a propeller shaft, a driven counter shaft operatively connected therewith, a sprocket on the counter shaft, a drive counter shaft spaced therefrom and parallel thereto, a sprocket on said drive counter shaft, a sprocket chain trained around said sprockets, manually operable means connected with the drive shaft comprising an upstanding supporting frame secured at its lower end to the hull of the boat, said frame including a stationary base section and a movable upper section normally projecting above the confines of the boat when the device is in active use and movable to a position within the confines thereof when the boat is in inactive use, 50 a manually operable crank shaft journaled

in the upper section of the framework having a sprocket secured thereto, a driven shaft journaled in the base section of the framework having a sprocket secured thereto and a sprocket chain trained around said 70 sprockets to permit of movement of the upper frame section to a position within the confines of the boat.

3. In a manually operable boat propelling apparatus, an upstanding supporting frame 75 secured at its lower end within the hull, said frame including a stationary base section and a movable upper section normally projecting above the confines of the boat and movable to a position within the confines thereof, a manually operable crank shaft journaled in the upper section of the framework having a sprocket and a crank handle secured thereto, a driven shaft journaled in the base section of the frame work having a sprocket secured thereto and a sprocket chain trained around said sprockets to permit of movement of the upper frame section to a position within the confines of the boat. 80

4. In a manually operable boat propelling 85 apparatus, an upstanding supporting frame secured at its lower end within the hull, said frame including a stationary base section and a movable upper section normally projecting above the confines of the boat and movable to a position within the confines thereof, a manually operable crank shaft journaled in the upper section of the framework having a sprocket and a crank handle secured thereto, a driven shaft journaled in the base section of the framework having a sprocket secured thereto, a sprocket chain trained around said sprockets to permit of movement of the upper frame section to a position within the confines of the boat and means for locking the upper frame section in its operating position. 90

5. In a manually operable boat propelling apparatus, an upstanding supporting frame secured at its lower end within the hull, said frame including a stationary base section and a movable upper section normally projecting above the confines of the boat and movable to a position within the confines thereof, a manually operable crank shaft 100 journaled in the upper section of the framework having a sprocket and a crank handle secured thereto, a driven shaft journaled in the base section of the frame work having a sprocket secured thereto, a sprocket chain trained around said sprockets to permit of movement of the upper frame section to a position within the confines of the boat and means for locking the upper frame section in its operating position and means for supporting the upper frame section in its inactive position. 105

6. In a manually operable boat propelling apparatus, an upstanding supporting frame secured at its lower end within the hull, said 110

- frame including a stationary base section and a movable upper section normally projecting above the confines of the boat and movable to a position within the confines thereof, a manually operable crank shaft journaled in the upper section of the framework having a sprocket and a crank handle secured thereto, a driven shaft journaled in the base section of the framework having a sprocket secured thereto, a sprocket chain trained around said sprockets to permit of movement of the upper frame section to a position within the confines of the boat, a propeller shaft having a screw propeller secured thereto and means operatively connecting said driven shaft and propeller shaft.
7. In a manually operable boat propelling apparatus, an upstanding supporting frame secured at its lower end within the hull, said frame including a stationary base section and a movable upper section normally projecting above the confines of the boat and movable to a position within the confines thereof, a manually operable crank shaft journaled in the upper section of the framework having a sprocket and a crank handle secured thereto, a driven shaft journaled in the base section of the framework having a sprocket secured thereto, a sprocket chain trained around said sprockets to permit of movement of the upper frame section to a position within the confines of the boat, a propeller shaft having a screw propeller secured thereto and means operatively connecting said driven shaft and propeller shaft, said means including a counter shaft, a sprocket and chain connection between the counter shaft and driven shaft, a stub shaft, a sprocket and chain connection between said stub shaft and the propeller shaft, pulley sheaves secured respectively to the counter shaft and stub shaft, guide sheaves and a flexible driving belt trained around said sheaves.
8. In a manually operable boat propelling apparatus, an upstanding supporting frame secured at its lower end within the hull, said frame including a stationary base section and a movable upper section normally projecting above the confines of the boat and movable to a position within the confines thereof, a manually operable crank shaft journaled in the upper section of the framework having a sprocket and a crank handle secured thereto, a driven shaft journaled in the base section of the framework having a sprocket secured thereto, a sprocket chain trained around said sprockets to permit of movement of the upper frame section to a position within the confines of the boat, means for locking the upper frame section in its operating position, means for supporting the upper frame section in its inactive position and means carried by the frame sections for preventing the displacement of the sprocket chain from the sprockets.

Signed at New York in the county of New York and State of New York this 5th day of April A. D. 1928.
